UNITED STATES PATENT OFFICE.

MILLER REESE HUTCHISON, OF NEW YORK, N. Y.

DESIGN FOR A SOUND-CONCENTRATOR.

SPECIFICATION forming part of Design No. 34,963, dated August 20, 1901.

Application filed July 19, 1901. Serial No. 68,985. Term of patent 14 years.

To all whom it may concern:

Be it known that I, MILLER REESE HUTCHISON, a citizen of the United States, residing at the city of New York, in the borough of Manhattan and State of New York, have invented and produced a new and original Design for Sound-Concentrators, of which the following is a full, clear, and exact description.

In the accompanying drawings, Figure 1 is a side elevation of a sound-concentrator constructed according to my new design, and Fig. 2 is a central section thereof.

The leading or material feature of my design consists of the cylindrical portion *a*, prolonged at one end by a pear-shaped extension *b*. The internal structure *c* is shaped with a bell or trumpet facing the end of the external

pear-shaped structure and then contracting into a tubular formation *c'*, which is curved to one side and appears on the outside of the ²⁰ external structure as a cylinder projecting therefrom.

Having described my invention, what I claim as new, and desire to secure by Letters Patent, is—

The design for a sound-concentrator as herein shown and described.

In witness whereof I subscribe my signature in presence of two witnesses.

MILLER REESE HUTCHISON.

Witnesses:

WALDO M. CHAPIN,
FRANK S. OBER.
